FILING CABINET DRAWER

Richard L. Gallagher, Erie, Pa.

Application June 2, 1947, Serial No. 751,921

4 Claims. (Cl. 312—273)

1

This invention relates generally to drawers for filing cabinets and it relates more particularly to collapsible front panels for filing cabinet drawers.

Front panels for filing drawers have heretofore been made in one piece thereby making it difficult for the filer to work over the top of the front panel, especially when the drawer is relatively high above the ground. Furthermore it has been difficult to get at files in the front part of the file drawer, especially when the file drawer is filled with filing envelopes. Files have been difficult to remove under these circumstances in that the upper part of the filing envelopes could not be moved laterally.

It is, accordingly, an object of my invention to provide a drawer for a filing cabinet having a front portion or panel in two complementary parts; the upper part being movable in telescoping relation to the lower part wherein the upper part of the panel is moved a distance equal to its height.

Another object of my invention is to provide a drawer for a filing cabinet having a collapsible front panel which is simple in construction, economical in cost, economical in manufacture and efficient in operation.

Another object of my invention is to provide novel means for lowering and raising the upper part of a two piece front panel for a filing cabinet drawer.

Another object of my invention is to provide novel ball-bearing means and races for the movable part of a front panel of a filing drawer.

Another object of my invention is to provide means for moving the movable part of a front panel of a filing drawer downwardly in telescopic relationship with the lower stationary panel upon a relatively short distance of opening movement of the drawer.

Other objects of my invention will become evident from the following detailed description, taken in conjunction with the accompanying drawings, in which:

Fig. 1 is a side elevational view of a filing cabinet with parts broken away for better illustration showing the upper drawer in an open position, and the lower drawer in a closed position;

Fig. 2 is a side elevational view of another form of collapsible front panel for a filing drawer with means for nesting the movable panel of the drawer in the lower stationary panel thereof;

Fig. 3 is an enlarged fragmentary top plan view taken on the line 3—3 of Fig. 2;

Fig. 4 is a vertical sectional view of another form of device for moving a movable panel of a

2

front filing drawer panel upon the opening and closing of the drawer;

Fig. 5 is a view taken on the line 5—5 of Fig. 4;

Fig. 6 is a fragmentary perspective view of the lower end of the guide channel shown in Fig. 4;

Fig. 7 is a fragmentary perspective view of the stop lug in the guide channel mounted on a cross-plate;

10 Fig. 8 is a fragmentary side elevational view showing the file cabinet drawer embodying my novel invention in an open position; and

Fig. 9 is a fragmentary view showing the slotted end of the flat spring member engageable by a lug on the movable panel.

Referring now to the drawings, Fig. 1 shows a filing drawer 1 having a lower stationary front panel 2 and an upper movable front panel 3 complementary to the lower panel 2 to form a straight

20 front panel on the filing drawer 1 when in a closed position. The movable panel 3 is connected to cam levers 4 pivoted at 5 which engage

rollers 6 journaled on stub shafts 7 fixed in the sides of the filing cabinet 8. The cam lever 4 has a cam surface 9 for raising the movable panel 3 to a position as shown in Fig. 2.

In operation, the cam levers are in a position as shown in Fig. 1 in closed position with the rollers 6 engaging the raised portions 10 of the cam levers 4. As the drawer 1 is pulled out-

30 wardly, the rollers 6 move downwardly on the camming surfaces 9 thereby lowering movable panel 3 to the open position shown in Fig. 1 after about 6 to 8 inches movement of the drawer 1 to an open position.

35 In Figs. 2 and 3 I have shown a drawer 12 carried by and movable in follower frame 13 of conventional design. The follower frame 13 normally moves at one half the speed of the drawer 12. A stationary box-like front panel 14 has a

40 movable panel 15 telescopically disposed for movement therein. The movable panel 15 has a depending portion 16 which is struck outwardly on each side thereof at 17 to provide for the dis-

45 position of ball members 18 between the struck out portion 17 and the front wall 19 of the stationary panel 14. A second set of ball members 20 is disposed between the flanged portions 21 of the inner wall 22 of the stationary panel 14 and the struck-out portions 17 of depending portion

50 16 of the movable panel 15. Cam rollers 23 are disposed on each side of the depending portion 16 of the movable panel 15 carried by flanged brackets 24 secured to the depending portion 16

55 of the panel 15 by welding or any other suitable means. Cam members 25 having rising portions

26 on the forward parts thereof are disposed on each side of the movable frame 13 and engage the cam rollers 23 to raise the panel 15 when the drawer 12 is closed.

In operation, as the drawer 12 is pushed inwardly to a closed position, the rollers 23 rise on the cam portions 26 of the cam members 25 and raise the movable panel 15 upwardly to the desired extended position to provide a complete straight front panel for the drawer 12. As the drawer 12 is opened the roller members 23 on each side thereof move downwardly on the cam portion 26 of the cam members 25 thereby permitting the movable panel 15 to telescope in the stationary panel 14 in approximately the first 6 to 8 inches of travel of the drawer as shown in Fig. 2.

In Figs. 4 to 9 inclusive, which is the preferred form of my invention, I have shown a movable panel 50 having an extension 70 connected by lug 71 to a comparatively heavy flat spring-like member 51 which moves in a right-angled guide member 52. The guide member 52 is slotted at 53 so that a member 54 carried by the cross frame member 55 will move in the guide member 52 when the drawer is moved to a closed position to force the spring-like member 51 forwardly thereby pushing the movable panel member 50 to an extended position upon the closing of the drawer. Lug 71 moves in slot 72 when the drawer is opened, the movable panel 50 will drop down by gravity or it may be pushed down when the member 54 moves rearwardly in the guide member 52. A drawer 75 is carried in a conventional cradle 76 which moves at a much less speed than the drawer 75, as shown in Figs. 4 and 8. The transverse member 55 is connected to the cradle 76 by fastening members 77 on opposite sides thereof. The abutting member 54 carried by the cross frame member 55 moves in the guide member 52 and also supports the horizontal portion thereof, the vertical portion of the guide member 52 being secured by a slight spot weld or any other suitable fastening means to the stationary lower front panel 78 of the drawer 75, this being the lower panel in which the movable panel 50 telescopes. The spring member 51 has a down-turned lip 79 which moves in the slotted portion 53 on the underside of the guide member 52. The bottom 90 of the drawer 75 is channeled in a conventional manner in order that a rod may extend longitudinally therethrough to hold the lower ends of file cards in a fixed position in the drawer. The cradle 76 moves on wheels 80 mounted on opposite sides thereof, the top side of the wheels 80 engaging a flange 81 on opposite sides of the drawer 75 in order that it moves relative to the cradle 76. Other wheels 82 carried by the cradle 76 engage the upper side of the flange 81 on the opposite sides of the drawer 75. The bottom of the drawer, the cradle, and the wheels are all conventional construction.

When the drawer 75 is opened as shown in Figs. 4 and 8, the drawer 75 usually moves at least twice as fast as the cradle 76 which carries the cross member 55 and the member 54 thereon which slides in the guide member 52. The member 54 moves rearwardly in the guide member 52 to free the spring member 51 so that the movable panel 50 falls downwardly by gravity 70 or it may be pushed down manually into the stationary panel 78 if desired.

It will be evident from the foregoing that I have provided and shown several different means for moving the top movable panel of a filing drawer to an open and closed position automatically upon the opening and closing of the drawer. Many other types of linkages, levers, cables and the like may be used for raising and lowering a movable front panel in telescoping relationship with a stationary panel forming the lower front panel of a file drawer without departing from my invention. Furthermore, linkages may be operated by rotation of the front handle to move the movable panel or it may be moved manually.

Various changes may be made in the specific embodiment of my invention without departing from the spirit thereof or from the scope of the appended claims.

What I claim is:

1. In a drawer for a filing cabinet, a collapsible front panel comprising a stationary lower portion and movable upper portion adapted to telescope in said lower portion, a comparatively flat member connected to said movable portion and extending downwardly and at right angles to said movable portion, a follower frame for said drawer, and means on said follower frame for engaging said flat member to move said movable panel upwardly upon the closing of said drawer.

2. In a drawer for a filing cabinet, as set forth in claim 1 wherein said flat member moves in a guide member.

3. In a drawer for a filing cabinet, a collapsible front side therefor comprising a stationary lower panel and a movable upper panel, the upper panel being movable downwardly to a position adjacent the lower panel, a flexible member connected to said movable upper panel and extending downwardly and at substantially right angles to the path of movement of said movable panel, a guide member for said flexible member, a follower frame for said drawer, and means on said follower frame for engaging said flexible member to move said movable panel upwardly upon the closing of said drawer.

4. In a drawer for a filing cabinet, a collapsible front side therefor comprising a stationary lower panel and a movable upper panel, the upper panel being movable downwardly to a position adjacent the lower panel, a comparatively flat flexible member attached to said upper movable panel and extending downwardly and at substantially right angles to the path of movement of said movable panel, a rectangular shaped guide member having the lower side thereof longitudinally slotted for slidably receiving said flat flexible member, a follower frame for said drawer, and means on said follower frame extending through the slot in said guide member to move said movable upper panel upwardly upon the closing of said drawer.

RICHARD L. GALLAGHER.
